(57) **CLAIM**

The ornamental design for a mouthpiece for carrying out respiratory medical test, as shown and described.

DESCRIPTION

FIG. 1 is a top view of a mouthpiece for carrying out respiratory medical tests according to the claimed design, the bottom view being identical thereto or a mirror image thereof;

FIG. 2 is a front elevational view of the mouthpiece shown in FIG. 1;

FIG. 3 is a rear elevational view of the mouthpiece shown in FIG. 1;

FIG. 4 is a left side elevational view of the mouthpiece shown in FIG. 1, the right side elevational view being identical thereto or a mirror image thereof;

FIG. 5 is a top view of the mouthpiece shown in FIG. 1 when separated into two parts, the bottom view being identical thereto or a mirror image thereof; and,

FIG. 6 is a left side elevational view of the mouthpiece shown in FIG. 1 when separated into two parts, the right side elevational view being identical thereto or a mirror image thereof.
